UNITED STATES PATENT OFFICE.

FRANK E. MORGAN, OF NEW HAVEN, CONNECTICUT, ASSIGNOR TO THE
NEW HAVEN CLOCK COMPANY, OF SAME PLACE.

DESIGN FOR A CLOCK-CASE.

SPECIFICATION forming part of Design No. 19,870, dated June 3, 1890.

Application filed October 14, 1889. Serial No. 327,019. Term of patent 7 years.

To all whom it may concern:

Be it known that I, FRANK E. MORGAN, of New Haven, in the county of New Haven and State of Connecticut, have invented a new 5 Design for Clock-Cases; and I do hereby declare the following, when taken in connection with accompanying drawing and the letters of reference marked thereon, to be a full, clear, and exact description of the same, and 10 which said drawing constitutes part of this specification, and represents a face view.

This invention relates to a design for clock-cases; and it consists in an octagonal face-board for a clock-case, having the several 15 divisions of its edge inwardly curved.

In representing my design I have shown a case ready to receive the clock-movement, the dial, and the dial-sash.

Referring to the illustration, the several 20 divisions of the edge of the octagonal face-board A are inwardly curved, the top, bottom, and side divisions being equal each to each in length, but longer than the intermediate

or corner divisions, which are also equal each to each in length. The drop B of the 25 case depends below the bottom division of the edge of the said face-board, and has straight parallel sides and a straight lower edge. As herein shown, the lower corners of the drop are inwardly curved to harmonize 30 the drop to the edge configuration of the face-board.

The essential and characteristic feature of my invention is, however, a face-board having the several divisions of its edge inwardly 35 curved.

What I claim is—

In the design for a clock-case herein shown and described, the octagonal face-board having the several divisions of its edge inwardly 40 curved, as illustrated and described.

F. E. MORGAN.
